UNITED STATES PATENT OFFICE.

ANTHONY HAAG, OF NEW YORK, N. Y.

BUILDING CONSTRUCTION.

SPECIFICATION forming part of Letters Patent No. 760,688, dated May 24, 1904.

Application filed November 17, 1902. Renewed November 10, 1903. Serial No. 180,629. (No model.)

To all whom it may concern:

Be it known that I, ANTHONY HAAG, a citizen of the United States, residing at New York, in the county of New York and State of New York, have invented certain new and useful Improvements in Building Construction; and I do declare the following to be a full, clear, and exact description of the invention, such as will enable others skilled in the art to which it appertains to make and use the same.

My invention relates to certain new and useful improvements in the construction of fire-proof or cement floors; and it consists in a hanger for supporting the temporary structure or form between the iron beams or girders upon which the concrete or cement flooring is to be laid.

The object of the invention is to provide a hanger of this character which is of simple and inexpensive construction, which will prevent the concrete or cement composition from shrinking away from the iron beams, and by means of which the temporary arch structure or form may be quickly and easily placed in position to support the concrete or cement and then removed after the same has hardened.

With these and other objects in view the invention consists of certain features of construction, combination, and arrangement of parts, as will be more fully described, and particularly pointed out in the appended claims.

In the accompanying drawings, Figure 1 is a perspective view of my improved hanger or stirrup. Fig. 2 is a side elevation of the same applied to an I beam or girder commonly used in the construction of buildings. Fig. 3 is a sectional view through a portion of a concrete flooring, showing my hanger supporting the temporary structure upon which the concrete flooring is laid. Fig. 4 is a similar sectional view after the flooring has hardened and the temporary arch or supporting structure has been removed.

Referring more particularly to the drawings, the numeral 1 denotes my improved hanger or clip, consisting of a single piece of metal or a metallic rod, preferably steel, bent as shown in the drawings. The horizontal end portions 2 and 3 are adapted to lie upon the top and bottom flanges of the metallic I-

beam 4, which is very generally used in building construction. The ends of these horizontal portions are bent, as shown at 5, to engage the flanges of the beams or girders. The vertical portion 6 extends parallel with the web 55 of the beam from the upper horizontal portion 2 to the lower flange of the beam, where it meets the lower horizontal portion 3, and from this point the two portions extend upwardly at an angle and parallel to form the 60 hook-like portion 7.

As will be seen upon reference to Fig. 3 of the drawings, when it is desired to lay a concrete or cement flooring the hangers are placed at proper intervals along the parallel 65 I beams or girders 4 of the floor with the hooked ends 5 engaging the upper and lower flanges of the beams. In this position the hook portions 7 extend inwardly to support the haunch-boards 8. The trusses 9, upon 70 which the temporary flooring 10 of the arch rests, are supported between the haunch-boards by the stirrup irons or hooks 11. The said irons or hooks are fastened to the ends of the trusses 9 and are adapted to hook over 75 or engage the top edges of the haunch-boards. When the temporary structure or form is thus arranged, the concrete or cement composition 12 is laid upon the same between the girders, as shown in Fig. 3. After the concrete or 80 cement flooring has hardened the temporary form or structure is removed by cutting off the hook portion at its lower end, as shown in Fig. 4. When this is done, the hook portions 7, the horizontal portions 3, the haunch-boards 8, the trusses 9, and flooring 10 will 85 drop, leaving the under side of the concrete flooring a smooth and finished ceiling. The vertical portion 6 and the upper horizontal portion 2 remain embedded in the flooring. 90

It will be observed that the vertical portion 6 and upper horizontal portion 2 sustain the best part of the weight and the lower horizontal portion 3 and its hooked end 5 hold the haunch-boards closely to the flanges of the 95 I-beams and prevent sagging. It will be further noted that the trusses 9 strengthen the hook portions 7 and the haunch-boards 8 and support them in the proper position.

By means of my invention the temporary 100

supporting structure or form may be easily and quickly erected with very little labor, and the trouble and expense of nailing up a new structure each time is obviated.

5 From the foregoing description, taken in connection with the accompanying drawings, it is thought that the construction, operation, and advantages of my improved building construction will be readily apparent without requiring a more extended explanation.

10 Various changes in the form, proportion, and the minor details of construction may be resorted to without departing from the principle or sacrificing any of the advantages of 15 this invention.

Having thus fully described my invention, what I claim as new, and desire to secure by Letters Patent, is—

1. A clip or hanger for the purpose described, comprising end portions provided each at one end with a hook to engage the flanges of a beam or girder and connected solely at their opposite ends, substantially as described.

2. A clip or hanger for the purpose described, comprising end portions, each having an engaging hook at one end, and a connecting portion between the other ends, and provided with an offstanding supporting-hook, 30 substantially as described.

3. In a device of the character described, the combination with beams or girders and a temporary supporting structure or form, of a clip or hanger provided with portions adapted 35 to engage the top and bottom flanges of the beams and with a doubled hook portion for supporting the temporary structure or form, said hook portions being adapted to be sev-

ered to permit of the removal of the temporary structure or form, substantially as described. 40

4. In a device of the character described, the combination with beams or girders and a temporary supporting structure or form, of clips or hangers formed of a continuous piece 45 of metal and provided with horizontal portions having hooked ends for engaging the flanges of the beam, with a doubled, severable hook portion for supporting the structure or form and with a vertical portion connecting 50 the upper horizontal portion and the hook portion, substantially as described.

5. The combination with beams or girders and clips or hangers having severable hooks, of haunch-boards adapted to be supported by 55 said hooks, trusses provided with stirrup irons or hooks adapted to engage the upper edges of the haunch-boards for supporting said trusses and a temporary flooring upon said trusses, substantially as described. 60

6. A clip or hanger for the purpose described, comprising portions to engage the top and bottom flanges of a beam, a vertical connecting portion, and an offstanding hook serving as a connection between said connecting portion and the portion for engaging the bottom flange of the beam, substantially as described. 65

In testimony whereof I have hereunto set my hand in presence of two subscribing witnesses. 70

ANTHONY HAAG.
